ATTORNEY

UNITED STATES PATENT OFFICE

DANIEL F. DALTON, OF WATERBURY, CONNECTICUT, ASSIGNOR TO THE SHOE HARD-
WARE COMPANY, OF WATERBURY, CONNECTICUT, A CORPORATION OF CONNECTICUT

FASTENING DEVICE

Application filed October 5, 1928. Serial No. 310,546.

This invention relates to fastening devices of the type wherein two edges of a fabric, such as in footwear, sweaters, coats, jackets and other articles, in which the edges of the article must be completely separable, are provided with fastening elements adapted to be successively interengaged or disengaged by operation of a slider.

One object of the invention is to provide means for properly locating the fastening elements of the two separable edges in position to be interengaged by operation of the slider.

Another object is to provide means for locating the coupling elements of the opposite edges in such relation that only a very slight movement of the slider will be necessary to begin the operation of interengaging the coupling elements.

Another object is to provide a device of the stated character embodying simplicity and low manufacturing cost.

Other objects and advantages will appear as the description proceeds.

Reference is to be had to the following specification and the accompanying drawings, in which:

Fig. 1 is a front elevation of a pair of completely separable stringers and disclosing the invention in association therewith;

Fig. 2 illustrates a stage in the connecting and separating of the stringers; and

Fig. 3 is an end view of the stringers and locating means.

Referring to the drawings which disclose one practical embodiment of the invention, reference characters 1 and 2 represent respectively two completely separable stringers which may be secured to the opposite edges of separable parts, such as the front edges of a sweater or coat, etc., the stringers being usually provided with beads 3 and 4 constituting their opposed edges and provided with rows of coupling elements such as those indicated at 5 and 6 adapted to be interengaged and disengaged by operation of a slider 7, which slider is generally equipped with a substantially triangular cam 8 cooperating with diverging side channels 9 and 10 of the

slider to interengage and disengage the coupling elements 5 and 6.

In stringers of the completely separable type, it is obvious that some means must be provided for so locating the opposed edges 5 or beads 3 and 4 that when the slider is operated the coupling elements 5 and 6 will be started to interengage each other at the proper point with respect to the bottom of the garment, so that the lower edges of the garment will be in alignment or disposed in any other relative position desired when the elements 5 and 6 are coupled together. For accomplishing this result, the bead 4 of the stringer 2 is provided with an eye 11 preferably of sheet metal bent to form, and including arms 12 clamped to the bead 4 and also having a pair of oppositely disposed side members 13 curved inward at their free ends substantially as illustrated in Fig. 3 and forming an opening. The opposite bead 3 is adapted to be inserted into the eye 11 and to extend beyond the bottom of the eye in substantial parallelism with the opposite bead 4. During insertion of the bead 3 into the eye 11, the slider 7 is brought to a lowered position as indicated in Fig. 2, whereby the bottom edge of the slider rests upon the uppermost one of the arms 12 of the eye 11, which in effect forms a stop for holding the slider in position and to prevent the same from dropping off of the stringer 2. In this lowered position of the slider 7, the channel 9 forms a guide-way for directing the bead portion 3 of the stringer 1 down into and through the eye 11 which is preferably loose fitting around the bead 3. A stop 14 is carried by the bead 3 and is adapted to engage the upper edge of the eye 11 so as to bring the first coupling element 5' of stringer 1 in position immediately beneath the triangular cam 8 and at a point to be engaged between the two lowermost coupling elements 4' attached to the bead 4 as will be understood upon a consideration of Fig. 2. By thus disposing the lower element 5' of the stringer 1 and the two lowermost elements 4' of the stringer 2 in close proximity to each other immediately beneath the cam 8, it is only necessary to move the slider upward a very short

distance to begin the operation of successively interengaging the coupling elements 5 and 6 of the two stringers. Also, when the slider 7 has been brought to its lowest position, that is, against the upper arm 12 which acts as a stop of the eye 11, the stringer 1 may be readily removed from the eye and withdrawn through the channel 9 of the slider, thus completely separating the two stringers. In order to facilitate insertion of the bead 3 into and through the eye 11, that portion of the bead 3 below the stop 14 is preferably stiffened. This may be accomplished by treating the above named portion of the bead with a solution of collodium, or the said portion may be reinforced by a metal ferrule, such as indicated at 15. Preferably a similar ferrule 16 is secured for symmetry of appearance to the portion of the bead 4 extending below the eye 11.

With the foregoing description it is evident that various alterations and modifications may suggest themselves to those skilled in the art without departing from the spirit 25 of the invention, and it is therefore not intended to limit the invention except as defined in the appended claim.

Having thus described my invention what I claim and desire to protect by Letters Patent is:

The combination with two completely separable stringers of flexible material having bead portions provided upon their edges with coupling elements adapted to be interengaged 35 and disengaged by operation of a slider, of an eye secured to the edge of one of said beads adjacent the bottom thereof, a portion of said bead below said eye being reinforced by a ferrule, the bead portion of the other 40 stringer being provided with a ferrule adapted to enter and pass through said eye, a stop immediately above said last named ferrule adapted to engage said eye whereby to position the coupling elements of said other 45 stringer in position to be interengaged with the coupling elements of the eye carrying stringer when said slider is operated, said ferrules being disposed substantially in parallelism and extending substantially to equal 50 depth below said eye when the coupling elements are interengaged.

Signed at Waterbury, county of New Haven, State of Connecticut, this 2nd day of October, 1928.
